UNITED STATES PATENT OFFICE.

JOSEPH T. RICE, OF KINGSTON, NEW YORK.

STEEL FORM FOR AND METHOD OF ENVELOPING WITH CONCRETE PIPE LINES AND THE LIKE.

Application filed March 19, 1924. Serial No. 700,226.

To all whom it may concern:

Be it known that I, JOSEPH T. RICE, a citizen of the United States, and resident of the city of Kingston, in the county of Ulster and State of New York, have invented certain new and useful Improvements in Steel Forms for and Methods of Enveloping with Concrete Pipe Lines and the like, of which the following is a specification.

10 My invention relates to steel forms and the method of applying them, to coat with concrete steel pipes and other curved surfaces.

15 In preparing forms for coverings for riveted steel pipe lines and other curved surfaces, the present practice is to use wooden forms or a unitary steel form. As to wood, the present practice is to prepare, fit and brace the forms as the work progresses and 20 the form and bracing are broken down after the cement has set. This has been very expensive, both in labor and material. In connection with steel forms, they have been of unitary character and so heavy as to require 25 the use of steam cranes to remove the forms, thereby necessitating the laying of the tracks on which the crane can work, or resetting the crane from time to time as the work progresses.

30 By my invention, I provide steel forms that are readily installed and removable, and capable of continuous and progressive re-use and being sectional in character, can be made of any length that the particular 35 job shows is desirable.

Another object of my invention is to obviate the destruction and refabrication of these forms on re-use.

40 Another object of my invention is to obviate the use of complicated bracings to support the forms while the concrete is being set.

45 Another object of my invention is to provide means to secure a minimum, predetermined space between the exterior surface of the pipe line and the outermost surface of the forms, in which space grout, cement or concrete may be poured to form the covering of the pipe line.

50 Another object of my invention is to so construct and arrange said forms that they may be readily assembled and disassembled by manual labor with a minimum expenditure of labor and materials.

55 Another object of my invention is to pro-

vide forms for a concrete envelope for steel pipes and other curved surfaces, this complete envelope being in contact at all points with the outer surface of the pipe line, preserves the pipe line by keeping it from rusting. By having the envelope of a predetermined minimum thickness sufficient strength is secured. On the other hand by limiting the thickness beyond that which is necessary for strength there is a great saving in the 60 concrete used.

In the drawings, Fig. 1 is a cross-section of the pipe line and forms.

Fig. 2 is a cross-section showing the tie rod.

Fig. 3 is a cross-section showing the locking pin or dog.

Fig. 4 is a cross-section of the line *a—a* Fig. 1.

Fig. 5 is a top view of the pipe line and 75 sections.

Fig. 6 is a detail showing the cradles.

Fig. 7 shows the arch rib.

Fig. 8 shows an arch plate and Fig. 9 is a section thereof.

Fig. 10 shows the base plate and Fig. 11 is a section thereof.

In the drawings, the riveted steel pipe line 1, is to be coated or enveloped with a concrete coating 2. While the drawings show a steel pipe line 1, it is obvious that my invention may be employed in coating or enveloping with concrete the outside of a curved tunnel or other continuous curved surfaces.

The form consists of straight base plates 5 having angle irons 8 and a filler 9 with rivets 10 to fasten together the angle irons, fillers, and base plates to form a groove in which the side plates may be inserted. The 95 plates 5 have footings 11 riveted to the base plates with the rivets 12^a, more particularly shown in Figs. 10 and 11.

The arch plates 7, are concave and have filler 12 and angle irons 13 riveted to the 100 plates to form grooves into which the next plate may be inserted, more fully shown in Figs. 8 and 9. The side plates 6, though straight, employ the groove construction of the arch plates so that arch plates and side 105 plates may fit together by a tongue and groove connection.

The arch ribs 4 are of angle iron and are contoured so as to allow for a minimum predetermined space between the outer pe- 110

riphery of the pipe line 1 and the innermost surface of the plates, to provide for the minimum thickness of the concrete envelope. Two of these arch ribs 4 are fastened end to end by bolts 15 and plates 15^a, or other fastening means and are hung over the spacing blocks 16.

As shown more particularly in Fig. 3 the plates are fastened to the arch ribs 4 by 10 locking pins or dogs 17 that fit around the arch ribs 4 and are driven into the holes 18 in angle iron 8. If the dogs do not fit tight enough against the arch ribs, ordinary wedges 31 may be driven in between the 15 dogs and arch ribs. The angle irons on the plates are not the full length of the plates in order to provide space at the center and ends thereof for the arch ribs 4 as indicated at 19.

20 If found necessary, additional bracing may be employed by placing an ordinary wooden beam between the bank and the plates as indicated at 28 in Fig. 1 or a beam may be placed longitudinally along the 25 plates as indicated at 29 and braces 30 at right angles thereto at intervals against said beam and against the bank.

To keep the plates from being forced out of the grooves in the underneath plates by 30 pressure of the concrete against the plates, I employ tie rods 20 as a reinforcing or stiffening means. This tie rod is slightly bent at one end 21, to fit into the hole 22, in one of the flanges of the angle iron. The 35 other end 23 is in the form of a wedge shape hook and being driven or wedged on to a flange of the angle iron of the plate below causes the plates to be locked in vertical alignment.

40 I employ a bulkhead form 24 which form is divided into four parts, bolted together, and the inner edge completely encircles the outer circumference of the pipe line 1. The outer edge of this bulkhead form 24 is in alignment with the outer edge of the arch ribs 4. The bottom edge of the bulkhead form 24 is in alignment with the bottom 45 edge of the cradle 3.

Said bulkhead form 24 is fastened on one 50 side by the arch rib 4 by means of clamps 25, more particularly shown in Fig. 4. On the other side it is held fast by collar 26 which fits around the pipe line 1, being tensioned there-against by the screw bolts 27.

55 In practice, the cradles 3 are first laid spaced apart, as indicated in Fig. 6. These cradles cannot be continuous, because the pipes are on the job in about 15 ft. lengths and must be riveted together. In order to 60 rivet the pipes there must be space around the circumference of the pipe for a workman to use a bucking-up hammer on the outside of the pipe, in the riveting operation.

The pipes then are riveted together in a 65 continuous pipe line and the water put there-

through under the usual pressure. Grout is then placed on the cradles shortly before the concrete envelope is to be put on.

Then the lowermost plates 5 are set on both sides of the pipe line for the distance 70 that the forms are to be used, it being understood that these forms are sectional in character and any length of form may be employed.

The spacing blocks 16 are placed on top 75 of the pipe line 1 at intervals of around seven and one-half feet in the case of a pipe line the inside diameter of which is eight feet ten inches. These arch ribs 4 hang loosely from the spacing blocks 16 and lower 80 spacing blocks are employed as shown at 16^a, Fig. 1. The base plates 5 are then clamped to the arch ribs 4 by means of dogs 17. The concrete is then put in and tamped under the bottom of the pipe lines to form 85 with the cradles 3 a continuous base for the pipe line 1. The side plates 6 are then inserted into the grooves of the base plates 5, said side plates are locked to the arch ribs 4 by means of the dogs 17 and are stiffened 90 and held into contact with the grooves in the base plates 5, by means of the tie rods 20. The concrete then is likewise poured. The same procedure is followed with regard to the side plates 6 and the arch plates 7. In 95 the form shown in Fig. 1 two lengths of concave arch plates 7 are employed on each side of the pipe line 1, leaving a space on top for which there are no plates.

Where the pipe line takes a quick bend, it 100 is necessary to remove a portion of the flange as indicated at 30, Fig. 10, similar portions being removed on the upper plates to permit the plates to telescope in order to obtain the change of direction.

The space at the top has the concrete set 105 on without the use of forms which are not needed at that place. This space without plates is shown in Fig. 5.

In pouring the concrete, as heretofore described, the spacing blocks 16 and 16^a are removed just before the concrete reaches them, the concrete taking the place of the spacing block.

Where the concrete is put in at the end of 110 a length of forms, the concrete would exude therefrom, if the bulkhead form 24 were not employed, so at the end of the series of forms as set up, the bulkhead form is placed, by being fastened to the arch rib 4 by means of clamps 25 and held in contact on the other side by means of the ring or collar 26. After 115 the concrete is set the plates, arch ribs, bulkhead form and other parts are removed and set up on the next section of the pipe line to be enveloped and the process of putting on the concrete repeated as here outlined.

By this method steel forms are made 120 standard, are easily applied and may be used again and again, without refabrication and 125 130

- without the usual complicated bracing. The forms are of such sizes as are capable of easy handling. The method of applying the cement covering or enveloping is continuous. 5 This method results in very material savings in labor, material and the time necessary to complete the enveloping with concrete of pipe lines, and the like.
- For convenience of description the foregoing specification has gone into details as to the dimensions of the forms having an inside diameter of eight feet ten inches. Such dimensions may vary under different conditions, and I do not limit myself to the dimensions herein set forth. 10
- It will thus be seen that there is herein described apparatus in which the several features of this invention are embodied, and which apparatus in its action attains the various objects of the invention and is well suited to meet the requirements of practical use. 20
- As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense. 25
- I claim:
1. In forms for enveloping with concrete pipe lines and the like, base, side and arch plates, means for connecting the contiguous edges of said plates, arch ribs supporting said side and arch plates, and means to space the inside periphery of the plates a minimum predetermined distance from the outer periphery of the pipe line. 30
  2. In forms for enveloping with concrete pipe lines and the like, base, side and arch plates, tongue and groove connections between the edges of said plates, arch ribs supporting said plates a minimum predetermined distance from the outer periphery of the pipe line. 45
  3. In forms for enveloping with concrete pipe lines and the like, base, side and concave arch plates, said side and arch plates being supported by the arch ribs, all said plates being connected together by tongue and grooves, reinforcing means to prevent the tongues from escaping from the grooves when said forms are filled with concrete, means for fastening said arch ribs to said base plates, means for fastening said side and arch plates to said arch ribs, and spacing means interposed between the inner periphery of the arch ribs and the outer periphery of the pipe line. 55
  4. In forms for enveloping with concrete pipe lines and the like, standard base, side and arch plates, means for connecting the contiguous edges of said plates, standard arch ribs, demountably fastened, and means to space the inside periphery of the arch ribs a predetermined distance from the outer periphery of the pipe line, all of said parts being interchangeable and capable of re-use for their respective purposes. 60
  5. In forms for enveloping with concrete pipe lines and the like, base, side and arch plates, demountably fastened, arch ribs, supporting said side and arch plates, means to space the inside periphery of the plates a minimum predetermined distance from the outer periphery of the pipe line, together with bulkhead forms encircling a pipe and demountable means for holding said bulkhead forms rigid. 65
  6. In forms for enveloping with concrete pipe lines and the like, longitudinal base, side and arch plates, tongue and groove connections between the edges of said plates, arch ribs supporting said plates, means to space the inside periphery of the plates a minimum predetermined distance from the outer periphery of the pipe line, together with bulkhead forms encircling a pipe and demountable means for holding said bulkhead form rigid. 70
  7. In forms for enveloping with concrete, pipe lines and the like, base, side and concave arch plates, said side and arch plates being supported by the arch ribs, said plates being connected together by standard connecting means, auxiliary reinforcing means to prevent the plates from separating when said forms are filled with concrete, means for fastening said side and arch plates to said arch ribs, spacing means interposed between the inner periphery of the arch ribs and the outer periphery of the pipe line together with bulkhead forms encircling a pipe and demountable means for holding said bulkhead form rigid. 75
  8. In forms for enveloping with concrete pipe lines and the like, standard base, side and arch plates, demountably fastened, standard arch ribs demountably fastened, means to space the inside periphery of the arch ribs a predetermined distance from the outer periphery of the pipe line, together with bulkhead forms encircling a pipe and demountable means for holding said bulkhead forms rigid. 80
  9. In forms for enveloping with concrete pipe lines and the like, in combination with a series of longitudinal forms, demountable bulkhead forms, said bulkhead forms on the inner edge encircling the pipe line, and being held rigid on one side by a demountable collar encircling the pipe line and on the other by being fastened by clamping pins to arch ribs, the outer edge of said bulkhead forms being in alignment with the arch ribs at the top and sides and at the bottom in alignment with the bottom edge of a cradle. 85
  10. In forms for enveloping with concrete pipe lines and the like, standard base, side and arch plates, means for connecting the contiguous edges of said plates, standard arch ribs, demountably fastened, and means to space the inside periphery of the arch ribs a predetermined distance from the outer periphery of the pipe line, all of said parts being interchangeable and capable of re-use for their respective purposes. 90
  11. In forms for enveloping with concrete pipe lines and the like, base, side and arch plates, demountably fastened, arch ribs, supporting said side and arch plates, means to space the inside periphery of the plates a minimum predetermined distance from the outer periphery of the pipe line, together with bulkhead forms encircling a pipe and demountable means for holding said bulkhead form rigid. 95
  12. In forms for enveloping with concrete pipe lines and the like, longitudinal base, side and arch plates, tongue and groove connections between the edges of said plates, arch ribs supporting said plates, means to space the inside periphery of the plates a minimum predetermined distance from the outer periphery of the pipe line, together with bulkhead forms encircling a pipe and demountable means for holding said bulkhead form rigid. 100
  13. In forms for enveloping with concrete pipe lines and the like, base, side and concave arch plates, said side and arch plates being supported by the arch ribs, said plates being connected together by standard connecting means, auxiliary reinforcing means to prevent the plates from separating when said forms are filled with concrete, means for fastening said side and arch plates to said arch ribs, spacing means interposed between the inner periphery of the arch ribs and the outer periphery of the pipe line together with bulkhead forms encircling a pipe and demountable means for holding said bulkhead form rigid. 105
  14. In forms for enveloping with concrete pipe lines and the like, standard base, side and arch plates, demountably fastened, standard arch ribs demountably fastened, means to space the inside periphery of the arch ribs a predetermined distance from the outer periphery of the pipe line, together with bulkhead forms encircling a pipe and demountable means for holding said bulkhead forms rigid. 110
  15. In forms for enveloping with concrete pipe lines and the like, in combination with a series of longitudinal forms, demountable bulkhead forms, said bulkhead forms on the inner edge encircling the pipe line, and being held rigid on one side by a demountable collar encircling the pipe line and on the other by being fastened by clamping pins to arch ribs, the outer edge of said bulkhead forms being in alignment with the arch ribs at the top and sides and at the bottom in alignment with the bottom edge of a cradle. 115
  16. In forms for enveloping with concrete pipe lines and the like, standard base, side and arch plates, means for connecting the contiguous edges of said plates, standard arch ribs, demountably fastened, and means to space the inside periphery of the arch ribs a predetermined distance from the outer periphery of the pipe line, all of said parts being interchangeable and capable of re-use for their respective purposes. 120
  17. In forms for enveloping with concrete pipe lines and the like, base, side and arch plates, demountably fastened, arch ribs, supporting said side and arch plates, means to space the inside periphery of the plates a minimum predetermined distance from the outer periphery of the pipe line, together with bulkhead forms encircling a pipe and demountable means for holding said bulkhead form rigid. 125
  18. In forms for enveloping with concrete pipe lines and the like, longitudinal base, side and arch plates, tongue and groove connections between the edges of said plates, arch ribs supporting said plates, means to space the inside periphery of the plates a minimum predetermined distance from the outer periphery of the pipe line, together with bulkhead forms encircling a pipe and demountable means for holding said bulkhead form rigid. 130

10. In forms for enveloping with concrete pipe lines and the like, base, side and concave arch plates, said side and arch plates being supported by the arch ribs, all said 5 plates being connected together by tongue and grooves, reinforcing means to prevent the tongues from escaping from the grooves when said forms are filled with concrete, means for fastening said arch ribs to said 10 base plates, means for fastening said side

and arch plates to said arch ribs, and auxiliary bracing means from the bank to the plates, and means interposed between the inner periphery of the arch ribs and the outer periphery of the pipe line.

15

Signed at New York in the county of New York and State of New York this 17th day of March A. D. 1924.

JOSEPH T. RICE.
